Application December 30, 1938, Serial No. 248,569

13 Claims. (Cl. 178—7.5)

My invention relates to television receivers or the like and particularly to television receivers of the projection type.

In designing television receivers of the projection type employing a cathode ray tube, one of the principal difficulties has been in obtaining a good quality projected picture which is sufficiently bright.

It is, accordingly, an object of my invention to provide an improved television receiver which will reproduce a picture of comparatively large size and of the desired brilliancy.

In practicing my invention I employ a spherical mirror for projecting the image appearing on a fluorescent screen, and provide a correcting plate to eliminate substantially all spherical aberration.

It has been previously proposed to project a television picture by means of a spherical mirror, by means of a mirror known as a Mangin mirror or by means of parabolic mirror. While these can be made to work at high speed optically, their use involves spherical aberration, chromatic aberration and coma, respectively, in all cases making the off axis images lacking in definition.

In my receiver a spherical aberration correcting plate permits the use of an aperture ratio of f.6, for example, or higher without any noticeable spherical aberration, chromatic aberration or coma. In other words, I provide a fast lens system of high quality. Furthermore, it is a lens system which absorbs a minimum amount of the light produced by the cathode ray tube.

As will be explained in detail hereinafter, the correcting plate and spherical mirror combination resembles the Schmidt camera which is used in astronomical work. However, in my system the correcting plate is ground or figured for a finite distance from mirror to projection screen whereas the corresponding distance in the Schmidt camera is infinity. Also, the object surface (the fluorescent screen) in my optical system as constructed up to this time does not, as in the Schmidt camera, have a radius equal to half the radius of the spherical mirror, but, instead, it has a curve which will focus any point on its surface on the image surface which ordinarily is a projection screen having a plane surface.

The invention will be better understood from the following description, taken in connection with the accompanying drawings in which

Figures 1 and 2 are diagrams which are referred to in describing the optical system employed in my improved receiver.

Figure 3 is a view, drawn substantially to scale,

of a television receiver embodying my invention. Figure 4 is a view, partly in section, of a portion of the receiver shown in Fig. 3.

Figure 5 is a view taken on the line 5—5 of Fig. 4, and

Figure 6 is a view illustrating another embodiment of my invention.

Referring to Fig. 1, there is illustrated a specific optical system which may be employed in a television receiver embodying my invention, specific dimensions being given merely by way of example. The system comprises a spherical mirror 1 and a correcting plate 2. The end of the cathode ray tube upon which the picture appears is indicated at 3 while the screen upon which the picture is projected is indicated at 4.

The correcting plate is figured to bring light rays reflected from either the edge of the mirror or from a point on or near its axis into focus at the projection screen. As in the case of the Schmidt camera, the correcting plate may have any one of several shapes although the shape illustrated is preferred. The way in which the correcting plate functions is illustrated in Fig. 2.

Referring to Fig. 2, it is assumed there is a light source at the point marked "focus." Light rays from this source reflected from the mirror 1 near its edge would have their focus at the point marked "normal edge focus" in the absence of the correcting plate 2. The correcting plate, however, is figured to refract these edge rays just enough to make them focus on the projection screen 4.

Considering the axial rays from the same light source, it will be seen that in the absence of the correcting plate they focus at the point marked "normal axial focus." The correcting plate is figured to refract these rays the correct amount to make them focus on the screen 4. Thus the correcting plate may be so figured as to make all rays originating from this light source and reflected from the mirror come to a focus on the projection screen.

Considering rays from a point on the picture or object 3 off the axis, the rays from a corner of the picture in order to focus on its corresponding corner of the screen 4 must have a shorter object focus and a longer image focus than the axial or central rays. Therefore, the radius of the object surface 3 will be greater than one-half the radius of the mirror 1. Thus, in the optical system shown in Fig. 1, it was found that the radius of curvature for the fluorescent screen on the end of the tube should be

10 inches where the radius of curvature of the spherical mirror was $17\frac{1}{4}$ inches.

The curvature of the object surface 3 may not be exactly spherical in some cases but it will be very nearly so. Of course, this curvature should be changed if the screen 4 is given a curvature instead of being flat as it ordinarily is.

The desired curvature for the object surface 3 may be obtained by placing a photographic plate on the axis of the optical system and then tracing a curve thereon by moving a spot of light, such as an electric bulb, along the projection screen and in a direction parallel to the plane of the photographic plate.

For example, referring to Fig. 1, a photographic plate may be positioned at the focus between the mirror 1 and the correcting plate 2 with the emulsion side up, i. e., the photographic plate is in the plane of the paper. Then the light from an electric bulb moved horizontally along the image surface 4 (i. e., moved in the plane of the paper) focuses on the photographic plate and traces the desired curve.

As to the technique employed in figuring and testing the correcting plate, it may be noted that, since my projection system focuses at a finite distance, it was found desirable to employ a testing procedure during the figuring of the plate based on the fact that the longitudinal spherical aberration of a high aperture mirror and the diameter of the pupil of the eye will make light from a pin hole at the focus appear to the eye placed on the axis at the second focus as a bright ring on the surface of the mirror. If the eye is placed on the axis at a point closer to the mirror, a ring of light of larger diameter on the mirror will be seen.

If we take a series of these annular zones or rings each having a focus on the axis and figure the correcting plate to bring them all to a focus at the same point, we have the required curve on the correcting plate. Thus, the procedure may be as follows:

Set up the system minus the correcting plate and, after placing a mark on the mirror at about .7 the distance from the center of the mirror to its edge, move the eye along the axis until the bright ring visible on the mirror passes through this .7 point. Adjust the foci until the bright ring passes through the .7 zone when the eye and pinhole are at the desired conjugate foci. When these adjustments are acquired, the bracket used for holding the correcting plate is placed so that first principal plane of the plate is at the center of curvature of the main mirror. A ray from the .7 zone of the main mirror should pass through the finished correcting plate without deviation and fall half way between the maximum and minimum foci of the uncorrected main mirror.

The reason for working from a zone .7 of the distance from the center of the mirror to its edge is that the area of the mirror inside this .7 ring is about equal to the mirror area outside this ring. Thus, the correcting plate may be figured to have a positive power for half the light and a negative power for the other half of the light whereby the refracting angles of the plate will be at a minimum for the desired correction. For all practical purposes, the .7 measurement may be taken on the chord from the center of the mirror to its edge.

The area of the correcting plate inside the .7 ring is then masked off and the negative power of the edge zone or .3 zone is increased by grinding until this zone focuses at the same place as

does the center or .7 zone. This edge zone, of course, is the area between the .7 ring and the edge of the mirror.

The progress of the grinding of the edge zone is checked from time to time by looking at the mirror from a point on the axis and noting the change in the position from which a certain ring of light is seen (this position being the focus for this particular ring of light). For example, if the eye is located on the axis at the point marked "Normal edge focus" (Fig. 2), a bright ring is seen near the edge of the mirror. After the edge zone has been worked on some by the grinding machine, it will be found that this ring of light is now seen from a point closer to the desired common focus. When this ring is seen from the desired common focus, the correction for the particular zone of the correcting plate through which this ring of light passes has been completed.

During the grinding of the edge zone, the other light rings of smaller diameter should be observed from time to time just as described in connection with the ring of largest diameter. When the rough grinding of this zone is finished, the entire edge zone will appear from the common focus to be covered with narrow rings.

After the edge zone is made to focus at the correct place, mask off this zone and work on the center or .7 zone and increase the positive power over this area until the rays falling beyond those of the .7 zone are brought into focus at the same place as those from the rest of the surface. In order to generate a curve continuous with that of the edge, it is best to work on the center portion beginning at the .7 zone.

It will be understood that the grinding of the center zone is checked in substantially the same way as described in connection with the grinding of the edge zone.

So far we have the general rough curve generated on the plate and we will find the entire surface covered with narrow rings. It is necessary from the beginning of this grinding operation to see that the plate is perfectly centered and running true on the grinding machine and frequent checks should be made to determine that the plate is maintaining a true surface of revolution.

It will be found that very narrow zones are capable of becoming tilted in relation to the general curve and may be detected by holding a screen about 2 inches inside the focus. A bright ring from a tilted zone will appear eccentric to the rest of the pattern. If the screen is moved to within a few inches of the plate and the finger used to cast a shadow, the zone responsible for the eccentric ring can be covered with the finger and the shadow followed from the plate to the focus as the screen is moved away. The tilted zone responsible for the ring can be interpreted into the direction of tilt on the surface of the plate which would cause the deflection of an annular cone of light creating the eccentric ring as found. Due to the fact that all errors appear in complementary illumination on opposite sides of the focus, it is best to do all testing inside the focus.

After the direction of tilt has been determined and the high portion located (by a scale placed in front of the correcting plate and by a corresponding one on the grinding machine), the plate is tilted on the turntable so that most work will be done on this zone.

The machine is arranged so that pressure is increased when the high zone comes under the grinding tool. After most of these narrow zones have been corrected, the plate, after being indicated true, is worked on with the largest tool possible with a radial stroke and the remaining narrow zones averaged out.

If desired, after the correcting plate has been figured as described above to bring all zones of the mirror close to the desired focus, a standard test such as the Foucault knife edge test may be employed for figuring the correcting plate still more accurately.

It was found that much time could be saved by coating the ground surface of the correcting plate with glycerine each time it was desired to make a test to permit testing without having to grind the plate to a smooth surface.

One practical embodiment of my invention is illustrated in Fig. 3.

Referring to Fig. 3, the television receiver comprises a cabinet 10 of the console type having a translucent screen 11, such as ground glass, in the front thereof upon which the reproduced picture is to appear.

A cathode ray receiver tube 12 of the projection type is mounted in the lower part of the cabinet with the fluorescent screen 13 facing a spherical mirror 14. Mounting supports for the tube 12 are shown at 16. The usual deflecting yoke is indicated at 17.

A correcting plate 18 is supported on a partition or shelf 15 and is positioned at or close to the center of curvature of the mirror 14 to bring the light rays originating at the fluorescent screen 13 and reflected from the mirror 14 to a focus on the screen 11 as explained in connection with Fig. 2. A mirror 19 is mounted at 45 degrees to direct the light rays from the correcting plate 18 to the screen 11.

Preferably, adjusting screws 20 are provided to facilitate axial adjustment of the correcting plate 18.

The loud speaker 21 and the receiver chassis 22 may be located in the receiver cabinet as indicated. With the above described receiver, a bright picture 15 inches by 20 inches of good quality may be obtained. It is assumed, by way of example, that the optical system of this receiver has the dimensions given in Fig. 1, the effective aperture being approximately .6.

It will be understood that the receiver shown in Fig. 3 may be designed to project a still larger picture upon a separate projection screen placed across across the room from the receiver, for example. In this case, the screen 11 is removed from the cabinet 10. Obviously, the correcting plate 18 should be figured differently for the different conjugate foci.

The mounting and adjusting means for the cathode ray tube 12 of Fig. 3 are shown more clearly in Figs. 4 and 5. The mounting supports 16 are in the form of a spider comprising four metal straps attached at their ends to the shelf 15. A metal cylinder 35 is welded or otherwise fastened to the inner ends of the spider arms 16.

The cylinder 35 has extending upwardly therefrom three lugs 36 for supporting the connecting plate 18 at the center. Such support may be desirable where the plate has been molded from a plastic such as Lucite.

The lower part of cylinder 35 has two slots 37 therein in which adjusting screws 38 may slide.

The tube 12 is supported from the cylinder 35

as follows: The deflecting yoke 17 fits over the neck of the tube 12 and the lower end of the yoke casing 39 clamps a member 41 between it and the enlarged end of the tube 12. The member 41 has a spherical surface for a reason which will soon be apparent, the radius r of the upper surface being the distance from this surface to the center of the end of tube 12 as indicated on the drawings.

10 In order to hold the yoke 17 in position, a wedge member 42 fits into the small space between the neck of the tube 12 and the yoke 17, the wedge being secured to the neck of the tube by a clamp 43.

15 The tube 12 and deflecting yoke 17 are supported from the cylinder 35 by means of a cylindrical member 46 which telescopes into cylinder 35 and is held in position by means of the screws 38.

20 The lower end of member 46 has an edge 47 spun or otherwise formed thereon which has a spherical surface conforming to the surface of member 41. Adjusting and fastening screws 48 pass through openings in the edge 47 and fasten in the member 41 in screw threaded relation, the said openings being large enough to permit an adjustment of the tube 12 about its lower end as a pivot.

25 From the foregoing, it will be apparent that by loosening the screws 38 the tube 12 may be moved axially to different positions, as indicated by the dotted lines, for the purpose of focusing the image upon the projection screen. Also, it will be seen that by loosening the screws 48 the tube 12 may be adjusted about the center of the lower end of the tube as a pivot point whereby the edges of the picture may readily be brought into focus.

30 In Fig. 6 there is illustrated another embodiment of my invention, this receiver being designed to project a picture upon a screen indicated at 26. In this figure the screen 26 is shown, much too close to the receiver because of limited space on the drawing.

35 The receiver comprises a cabinet 27 which may be either of the table model or console type. A cathode ray tube 28 is positioned in front of a spherical mirror 29 in the proper relation to project the image appearing on the end of the 40 cathode ray tube upon the screen 26. A correcting plate 31, as previously described, is mounted at the front of the cabinet. The tube 28 preferably is adjustably mounted as previously described.

45 If the cabinet is of the console type as illustrated, the loud speaker may be located in the lower part of the cabinet as indicated at 32 or remotely, as desired. The receiver chassis 33 may be mounted in the top of the cabinet as shown, or it may be located along one side of the cabinet if the cabinet is made of sufficient width.

I claim as my invention:

1. An optical system for image projection and enlarging comprising a light source adapted to emit light according to Lambert's law to produce a bi-dimensional optical picture image of finite area substantially centered on the optical axis of the system, a light reflecting surface of revolution having its concave surface positioned to receive the light issuing from the source, an aspherical zone plate positioned to receive the reflected light projected from the light source, said zone plate being arranged external to the light path from the light source to the reflector and axially aligned with each and adapted to cor-

rect the spherical aberrations introduced into the reflected light rays by the reflecting surface whereby a sharply focused enlargement of the original finite dimension light source is developed at a plane located at a finite distance from the aspherical zone plate.

2. An image projection device comprising a light source of finite bi-dimensional image area emitting light according to Lambert's law, an axially aligned optical system including a concave reflecting surface of revolution positioned to receive the light issuing from the source, and an aspherical zone plate positioned external to the path of the light projected from the light source to the reflector and positioned to receive 15 the reflected light from the reflector, said zone plate being adapted to correct for spherical aberrations introduced by the reflecting surface whereby the optical system projects a sharply defined enlarged image substantially free from 20 spherical aberration upon a viewing surface located at a finite distance from the zone plate.

3. An image projection device comprising a cathode ray tube to produce a light image, and an aligned optical system including a spherical 25 reflector element having its concave surface area positioned to receive the light image from the tube and an aspherical zone plate located at substantially the center of curvature of the spherical reflector element to receive the light image as reflected thereby, said zone plate being located external to the light path from the tube to the reflector and having such curvature as to correct for spherical aberration introduced into the reflected light rays by the reflector whereby the optical system including the reflector and the zone plate is adapted to form a projected enlarged image of the light image upon the cathode ray tube upon a viewing area located at a finite distance from the zone plate.

4. A television image projection device comprising a cathode ray tube having a luminescent target area whereupon an optical image is produced, a spherical reflector having its concave surface area positioned to receive the light of the image as produced upon the cathode ray tube, an aspheric zone plate located external to the tube to reflector optical path and arranged to receive the reflected light from the reflector, said zone plate having its surface area of such curvature as to correct for spherical aberration due to the reflector so that a sharply focused enlarged image of the tube target area may be focused upon a viewing surface located at a finite distance from the zone plate.

5. The device claimed in claim 4 wherein the said zone plate is located substantially at the center of curvature of the reflector.

6. In a television image projecting and enlarging apparatus, a cathode ray tube having means to produce light representative of an image, an aligned optical system to receive the light image on the tube, said optical system including a substantially spherical light reflecting element having its concave surface positioned to receive the light from the light source, and an aspherical plate member located external to the tube to reflector light path to receive the reflected light from the reflector and located near or at the center of curvature of the reflector, said aspherical member being so curved as to correct for spherical aberrations introduced by the reflecting means, said plate curvature being such as to reduce the said spherical aberration

to a minimum in a viewing area located a finite distance from the said plate member.

7. The apparatus claimed in claim 6 wherein the said aspherical plate member has a central aperture and wherein at least a portion of the said cathode ray tube projects through the said plate.

8. The apparatus claimed in claim 6 comprising in addition means for pivoting the cathode ray tube about a pivot point located substantially at the center of the thereupon produced light image to adjust the said tube relative to the light reflecting and projecting elements of the optical system.

9. A television image projector and enlarger comprising a cathode ray tube having a luminescent target area of finite dimensions whereupon a two dimensional optical image is adapted to be produced, said optical image being adapted to radiate light substantially according to Lambert's law, a substantially spherical light reflecting means axially aligned with the axis of the tube and so positioned that the light rays of the image upon the tube are adapted to fall upon the concave surface of the reflector, and a spherical aberration correcting means for correcting for spherical aberration introduced by the said spherical light reflecting means, said means comprising a zone plate member having its surface of predetermined curvature to compensate for the said spherical aberration distortion and spaced from the reflector by a distance approximately equal to the radius of curvature of the reflector, said zone plate being located external to the light path between said cathode ray tube and the reflector and so positioned that the said tube masks only the central area of the said plate, whereby the optical system is adapted to focus an enlarged projected image of that upon the tube upon a viewing surface located at a finite distance from the light source and optical system.

10. In a television image projecting and enlarging apparatus, a cathode ray tube having a neck portion and a target portion whereupon an optical image is adapted to be produced, an optical system aligned with the tube axis, said system including a substantially spherical reflecting element positioned to receive the light 45 from the tube target, and an aberration correcting zone plate element located substantially at the center of curvature of the reflector and having its surface so curved as to correct for spherical aberrations introduced by the reflecting 50 means, said surface being positioned externally of the light path between the light source and the reflector and arranged to receive light directly from the reflector, said plate being also so curved that the spherical aberration is a minimum upon an image viewing area located 55 at a finite distance from the optical system.

11. The apparatus claimed in claim 10 wherein said zone plate has its central area apertured and wherein the said tube neck is projected 60 through the plate aperture.

12. The apparatus claimed in claim 10 comprising in addition means for pivoting the cathode ray tube about a pivot point located substantially at the center of the thereupon produced light image to adjust the said tube relative to the light reflecting and projecting elements of the optical system.

13. In television image projection apparatus, a cathode ray tube device having a luminescent target area and means to produce on the target

two dimensional light images, an aligned optical system including a reflecting element comprising a surface of revolution having its concave area positioned to receive the light from the light source, and an aspheric aberration correction means comprising a plate element having its surface area of such curvature as to correct for spherical aberrations introduced into the reflected light by the reflecting means and located near or at the center of curvature of the light 10

reflecting element, said surface being positioned externally of the light path between the cathode ray tube light source and the reflector and arranged to receive light from the reflector, and 5 said optical system being adapted to focus the enlarged image sharply and with minimum spherical aberration upon a viewing plane located at finite distance from the correction plate.

DANIEL O. LANDIS.
